[57] CLAIM

The ornamental design for a needle disposal container, substantially as shown and described.

DESCRIPTION

FIG. 1 is a front elevational view of a needle disposal container according to my invention;

FIG. 2 is a top plan view thereof;

FIG. 3 is a side elevational view thereof, from the right of FIG. 1;

FIG. 4 is a side elevational view of the opposite side thereof;

FIG. 5 is a bottom plan view thereof;

FIG. 6 is a rear elevational view thereof; and,

FIG. 7 is a front elevational view of a second form of needle disposal container according to my invention, the remaining views being identical to FIGS. 2-6, respectively.

Fig. 1.

Fig. 2.

Fig. 5.

Fig. 6.

Fig. 7
